AUTOMATIC DIALING TELEPHONE ATTACHMENT

Harry Aaron, New York, N. Y., and John Hammerstrom, Bridgeport, Conn.; said Hammerstrom assignor to said Aaron

Application October 10, 1936, Serial No. 104,946

8 Claims. (Cl. 179—90)

This invention relates to an automatic dialing device, and more particularly to one which is portable and may be readily and detachably associated with a conventional automatic dial telephone. The invention still further relates to such a dialing device which may be selectively operated by the user to automatically dial telephone call numbers selected by the user from a pre-established group of such telephone call numbers.

Conventional automatic telephones are provided with dials, the successive selective rotation of which sets up electrical impulses in pre-established sequence to thereby actuate call number selecting mechanism relating to the specified telephone call number.

The dial of such conventional telephone is provided with a selected number of stations arranged on its periphery, usually ten in number, each station corresponding to a letter or a number, which, in a specific sequential arrangement, corresponds to a telephone call number. Rotation of the dial, which is operatively connected to an impulse mechanism and which mechanism functions by the successive closing and opening of an electric circuit, to any selected station, sets up the number of impulses corresponding to that station. To dial a telephone number, the operator rotates the dial successively to each letter or number station in sequence corresponding to the combination comprising the telephone number, the dial, upon being released at each selected station, spontaneously returning to its original position by spring actuated means. The return movement of the dial opens and closes an electrical circuit successively to thereby set up the number of impulses relating to that particular station.

In certain commercial offices, such as those of bakeries, dairy companies, or like large organizations, the same telephone call numbers are dialed each day. For example, in large cities, in order to ascertain the requirements of its product for that day, it is usual for a dairy company each morning to telephone its regular and established customers, who may number hundreds or thousands. The dialing of a hundred or more telephone numbers from a regularly established list in a given period is tiresome and tedious work and, because of the human difficulty in successively memorizing or mechanically dialing so numerous a selection of telephone numbers, is attendant with errors in dialing which are time-consuming and costly.

Our invention contemplates the provision of a

portable attachment, compact in structure, which may be detachably associated with a conventional automatic dial telephone, and which on operation will selectively engage the dial thereof, to automatically operate the said dial in proper sequence to correspond to any telephone call number selected from a pre-established group of such numbers.

Our invention further contemplates the provision of means corresponding to a selected telephone call number which may be readily and conveniently inserted in or removed from the device, and which means actuate the device mechanism to influence the selective actuation of a telephone call number selecting mechanism.

The invention still further contemplates the arrangement on the device of a pre-established group of such telephone call number selecting mechanism influencing means and the provision of means for volitionally selecting from such pre-established group any one device mechanism actuating means corresponding to a desired telephone call number.

Broadly, therefore, our invention contemplates the provision of a device which will automatically obtain a telephone call number volitionally selected from a pre-established group of such call numbers.

Further objects of our invention will be clear from the description which follows and from the drawings wherein like reference characters refer to like parts throughout the several views and in which

Figure 1 is a front elevation of our automatic dialing device in operative association with a conventional automatic dial telephone.

Figure 2 is a top plan view of our automatic dialing device with the enclosing casing and housing removed and disclosing the motor and operating mechanism.

Figure 3 is a side elevation looking toward the line 3—3 of Figure 2, with the dial engaging clutch actuating cams partially broken away.

Figure 4 is a top plan view of the dial engaging clutch and operating gear, the cover thereof being partially broken away.

Figure 5 is a fragmentary cross section taken along the line 5—5 of Figure 2.

Figure 6 is a view similar to Figure 5, but with the motor switch disconnecting means in position just prior to disconnecting the switch.

Figure 7 is a fragmentary cross section taken along the line 7—7 of Figure 3.

in dotted lines the dial engaging clutch in dial engaging position.

Figure 9 is a section taken on the line 9—9 of Figure 8.

5 Figure 10 is a cross section taken along the line 10—10 of Figure 1.

Figure 11 is a profile view of a dial actuating cam.

10 Figure 12 is a rear elevational view of the dial engaging clutch and its operating mechanism.

Figure 13 is a side elevational view thereof.

Referring now to the drawings, the preferred embodiment of our invention is provided with the operative mechanism enclosing casing 10, the cover plate 12 of which provides a platform to support a conventional automatic dial telephone hand set 14 in operative association with the dial engaging and driving friction clutch 22.

Extending from the casing and detachably secured thereto in any suitable manner as by the lock screw 17 to thereby permit ready access to the operative parts is the housing 16 which encloses and houses a pre-established group of cam wheels arranged to operate the device to thereby 25 selectively actuate the telephone call number selecting mechanism.

In operation, the telephone hand set is arranged on the cover plate and held thereon in any suitable manner as, for example, by means 30 of the spring influenced rubber covered lugs 18 disposed around the periphery of the platform and which are urged against the base 19 of the telephone to thereby firmly hold it in position. The lugs are so arranged on the cover that the telephone dial is properly positioned relatively to the friction clutch for operative cooperation therewith upon arranging the telephone on the platform.

It will, of course, be understood that the particular type of telephone shown on the drawings is for purposes of illustration only and that our novel device may be associated with any type of telephone hand set.

The invention contemplates the provision of 45 means which will automatically engage the telephone dial 20 and selectively rotate it to each of a series of stations in proper sequence corresponding to the desired telephone call number. Such means are embodied in the rotating wheel 50 friction clutch 22, which is normally stationary and disposed disengaged from the dial in the position illustrated in Figures 1 and 8. In automatically dialing any number, the clutch is rotated and successively and in proper sequence 55 swung back and forth about the countershaft 24 as a pivot into operative engagement with and disengagement from the dial, which enters the groove 26 arranged on the rim of the clutch, by the selectively cam actuated mechanism which 60 will in detail be described below.

The dial engaging groove is preferably formed on the periphery of the tire 28, which is detachably arranged on the wheel in order to permit ready replacement thereof, and is constructed 65 from any frictionable material such as rubber.

As the rotating clutch engages the telephone dial upon being swung about the shaft 24, it rotates the dial to the proper selected station. Upon the dial reaching this position, the clutch is 70 swung away from the dial, thereby releasing the dial and permitting it to return to its normal position, thereby causing the required impulses corresponding to that selected station to be set up in the telephone call number selecting mechanism.

This operation is repeated and the dial rotated in proper station sequence until the telephone call number is automatically dialed after which the friction clutch is returned to its normal stationary position disengaged from the dial. 5

It will, of course, be understood that, if desired, our novel selective actuating mechanism may be connected directly to the telephone call number selecting mechanism itself, thereby eliminating the wheel friction clutch and the dial. 10

The working parts are preferably operated by a conventional electric motor 30, of any suitable type, which is housed in the casing on the supports 32 upstanding from the base 34, and which is connected to any convenient source of electric 15 current by the cord 35. The motor, which need not be described in detail here since such details, per se, constitute no part of the present invention, may be secured to the supports in any convenient manner as by means of the screw bolts 36. 20

Power from the motor to drive the working parts of the device, namely the rotating wheel friction clutch and the clutch selectively actuating mechanism, is transmitted through the transmission gearing, which likewise is supported in the 25 base of the casing.

The transmission gearing housing or frame comprises the walls 38 and 40, which are preferably cut away at their centre portions to reduce weight and to permit the worm wheel 42 to be 30 disposed therebetween.

It will be understood that the transmission gear train described herein is primarily arranged to operate the specific friction clutch and clutch selectively actuating mechanism disclosed, which 35 may be arranged relatively to each other in a variety of ways, depending on many factors such as the specific construction of these parts, space requirements to be allotted thereto, and the like and, therefore, serves for purposes of illustration 40 only since it and the specific arrangement of the parts may be varied without changing the scope of the invention herein set forth.

The motor shaft 44 is operatively connected to the transmission main driving shaft 46 in any 45 suitable manner as by means of the toothed clutch 48 (see Figure 2).

Arranged on the driving shaft is a worm gear 50 which operatively meshes with the worm wheel 42 on the substantially vertical countershaft 24 50 which is journaled in the bearing blocks 52 and 54. The bearing blocks are housed in the frame and secured to the cam shaft support 56 of the frame wall by the plate 58 which is held thereon in any suitable manner, as by screw bolts, rivets 55 or the like.

It will be understood that since the dial of the conventional telephone set is disposed at an angle to the horizontal, the countershaft, about which the rotating wheel clutch is swingable, is therefore arranged to extend upwardly at such an angle to the vertical that the wheel clutch will be disposed outwardly of the casing parallel to and in the same horizontal plane as the dial. The length of the countershaft is such that the 65 groove of the friction clutch will engage the rim of the dial when the clutch is swung about the countershaft.

It will be apparent that upon arranging the telephone hand set on the platform, the dial and 70 wheel clutch will then be disposed adjacent to and relatively to each other in operative engaging position.

Arranged on the upper end of the countershaft is the wheel friction clutch driving spur gear 75

which is fixed thereon as by means of the set screw 62 arranged in the spur gear hub 64.

The driven spur gear 66 is rotatably arranged on the wheel friction clutch shaft 74 and is secured to the under face of the friction clutch by the cap screws 68.

The friction clutch and associated driven gear are supported on the rocker arm 70, which will be described in greater detail hereinbelow, and together rotate on the shaft 72, which is secured in operative cooperation with parts to the rocker arm by the end cap 74 and the nut 76 which is arranged on the threaded end 78 of the bearing shaft. (See Figures 10, 12 and 13.)

In order to prevent exposure of the friction clutch and operative gear, we arrange thereover the protective cover 79, which is slotted to frictionally receive the end cap of the clutch shaft to be thereby secured thereon.

It will be apparent that operation of the electric motor will, by means of the transmission gearing, impart rotation of the wheel friction clutch about the shaft 72 in a counterclockwise direction, thereby rotating the telephone dial when it is brought into engagement therewith, the dial rotating in a clockwise direction.

In order, therefore, to automatically dial a telephone call number, it becomes necessary to provide a mechanism which will throw the friction clutch into engagement with the dial and maintain such operative engagement of these members until the dial is rotated to the first station of the telephone call number combination, at which position the mechanism will operate to swing the clutch out of dial engagement and thereby permit the dial to return to its normal position and which will successively repeat such operations to thereby in proper sequence rotate the dial successively to each of the remainder of the stations of the call number.

Referring now to the mechanism for swinging the wheel friction clutch into and out of engagement with the dial, the rocker arm 70 is arranged on the sleeve 80 extending therefrom through which the vertical countershaft extends and in which it is rotatably journaled. (See Figure 10.) The sleeve itself is pivotally journaled in the bearing block 54 so that it is rockable thereabout.

Extending from the sleeve and fixed thereto by means of the cap screw 82 in the collar 84 is the sleeve actuating arm 86, which rocks the sleeve 80 about the shaft 24 and through it the rocker arm 70. (See Figures 7, 8 and 12.)

Arranged on the support 56 is the block 88 in which is fixed the pivot shaft 90 about which the bell crank lever 92 is swingable.

Fixed to the substantially horizontal arm 94 of the bell crank lever 92 is the cam actuated arm 96 which is pivotally arranged on the fixed pivot shaft 90.

Extending from the arm 96 is the ratchet bar 98, which is thereby adapted to be rocked about the pivot shaft in a manner to be described.

The telephone number selecting indicator frame 100 is movably secured to the ratchet bar, the beveled guide 102 slidably held in a cooperating channel on the rack and carries the index finger 104, (see Figures 1 and 3) which is arranged above and adjacent to the index scale 105.

Extending from the indicator frame and rotatably arranged therein is the shaft 106 on the inner end of which is secured the pinion 107, in engagement with the rack 108 of the bar and on the outer end of which is the knurled knob 109.

It will be apparent that the index finger may

be moved laterally on the bar to thereby dispose it adjacent any selected position on the scale by the proper rotation of the knob. It will be further apparent that the bar and index finger structure is arranged to be swung back and forth about the pivot shaft in the directions indicated by the arrows in Figures 3 and 5.

Extending underneath the indicator frame is a cam follower 110 which, upon depressing the indicator frame in the direction indicated by the arrow in Figure 3 swings the bar and its associated members about the pivot shaft thereby bringing the cam follower into engagement with the depressed surface 111 of a selected rocker cam wheel 112 corresponding to a selected telephone number.

The flat spring 114, the movable end of which is secured to the pin 116 on the lower end of the arm 118 of the rockable bell crank lever and the fixed end of which is secured to the pin 120 of the wall 38, normally maintains the cam follower against the face of the cam during operation of the device.

Depression of the indicating frame against the cam wheel closes the motor electrical circuit in 25 a manner that will be described in greater detail hereinbelow and simultaneously disposes the friction clutch into operative engagement with the telephone dial. This is accomplished by means of the levers and links heretofore referred to, the 30 operation of which will now be described.

The substantially vertical arm 118 of the bell crank lever has fixed thereto the link pin 122 which is arranged in the somewhat elongated slot 124 of the ear 126 depending from the sleeve 35 actuating arm 86. Movement of the substantially vertical arm 118 in the direction indicated by the arrow in Figure 13 swings the sleeve actuating arm in the direction indicated by the arrow in Figure 8, thereby swinging the rocker 40 arm and its associated friction clutch to the left into operative engagement with the telephone dial. The arc required to be described by the rocker arm is very slight, thereby permitting the lateral rocking motion of the bell crank lever 45 arm to be translated into the rotary rocking motion of the sleeve actuating arm by means of the link pin and slot arrangement.

The invention contemplates the provision of means for rotating the friction clutch in such 50 operative engagement with the dial and maintaining it in engagement until the dial is rotated to the desired station, at which position it is contemplated that the friction clutch shall be released from operative engagement with the 55 dial.

The invention further contemplates maintaining the friction clutch in such disengaged position until the dial returns to its normal position, at which time the friction clutch is to be 60 returned into operative engagement with the dial which is thereby to be again rotated to the next station forming part of the call number sequence.

It is, therefore, contemplated to arrange such 65 means so as to provide the successive sequential measured engagement and disengagement of the friction clutch with the telephone dial which will result in the automatic dialing of a selected call number.

Such successive sequential measured actuation of the friction clutch is accomplished by the action on the cam follower 110 of a rotating rocker cam wheel 112 fixed on the cam shaft 128.

In order to simultaneously drive the cam shaft and rotate the friction clutch, the worm gear 130 is fixedly secured to the countershaft intermediate the bearing block 52 and the rocker arm sleeve 80 and meshes with the worm wheel 132 secured to the cam shaft. (See Figures 3 and 10.)

The cam shaft is rotatably arranged in suitable bearing journals in the supports 56 and 134 extending upwardly from the walls of the transmission gearing frame. A collar 136 is secured to the shaft by the set screw 138 and together with the spacer 140 inhibits lateral motion of the cam shaft in the frame.

It will be apparent that any number of such cam wheels, each corresponding to a particular telephone call number, may be arranged on that part 142 of the cam shaft extending from the side of the casing, the only limitation being that of dimensional restriction.

The profile of each of such cam wheels is alternatively provided with a plurality of depressed cam surfaces 144 and cam noses 146, the purpose of which will become apparent. (See Figure 11.)

It will be understood that as long as the cam follower is urged by the flat spring against a depressed cam surface, the friction clutch is correspondingly held in engagement with the telephone dial. As the cam shaft is rotated in a counterclockwise direction by the motor, the cam follower is held against the profile cam surface by the flat spring. The circumferential length of each depressed surface on the cam wheel corresponds to the circumferential length of travel of the telephone dial to dial a particular number or letter. The circumferential length of a nose on the cam will be such as to permit a length of time to elapse only sufficient to permit the dial to return to its normal position after its rotation to the selected station. The exact dimension will depend upon the gear ratios and the diameters of cam wheel and friction clutch used.

It will be apparent then that such a cam may be provided for each selected telephone call number by arranging on the profile of the wheel a series of depressed surfaces of measured lengths each respectively corresponding to the circumferential length from the telephone dial finger stop of the particular station to be dialed, the said depressed surfaces separated by cam noses of measured lengths each respectively sufficient to permit the elapse of the period of time required for the dial to return to its normal position after rotation thereof to the preceding station dialed. For example, referring to Figure 11, the assumed telephone number combination is BDAF. In operation, the cam follower is depressed and held by the spring against the depressed surface 144 of the cam adjacent the letter B in Figure 11, which is of length sufficient to permit the telephone dial to be rotated from the dial station B to the finger stop 148 on the telephone hand set. As the cam follower engages the beveled edge 150 of the nose of the rotating cam, the cam follower is lifted against the tension of the flat spring, thereby disengaging the friction clutch from the dial. The height of the nose is just sufficient to permit disengagement of the clutch; it not being intended to return the clutch to its full normal position, for reasons which will be indicated hereinbelow. The circumferential length of the nose 146 is at least sufficient to permit the full return of

the dial to its normal stationary position. As the cam is rotated further, the cam follower engages the rearward beveled edge 152 of the cam nose, the flat spring urging it downward against the depressed portion corresponding to the letter D of Figure 11. The friction clutch is thereby again urged into engagement with the telephone dial, the circumferential length of the depressed surface D corresponding to the circumferential length of the station D to the finger stop 148. The friction clutch is held in operative engagement with the dial which is thereby rotated to the position corresponding to the station D, upon completion of which rotation the cam follower engages the nose 154 to thereby again release the dial. This operation is repeated until the stations BDAF in the proper sequence have been dialed, after which the cam follower engages the last cam nose 156 to thereby release the friction clutch, the number having been dialed. Means, which will be further described in detail, are provided for stopping operation of the motor after the number has been dialed.

In operation, a plurality of cam wheels, each wheel corresponding to a particular telephone call number of the pre-established group of frequently dialed call numbers, are detachably arranged on the cam shaft which extends through the aperture 158 arranged centrally of the cams and securely held thereon by the lock nut 160 which engages the threaded end 162 of the cam shaft. Washers 169 are interspaced between the cam wheels, which frictionally hold the wheels on the shaft.

The rocker cam wheels may be arranged on the cam shaft in any desired sequence, provided their exact position thereon is noted. The index scale 105 has provided thereon reproductions of the telephone numbers comprising the group corresponding to the cam wheel which is arranged thereunder and which it designates. If desired, such reproductions may be replaced by indicia, each item of which corresponds to a selected cam wheel and, therefore, to a selected telephone number and an index code made of the indicia.

The cam wheels are so arranged on the shaft relatively to the scale that, upon moving the index finger above any number or item of the scale, the cam follower will be placed in operative position adjacent the cam wheel corresponding to the selected item or number on the dial.

In order to assist in positioning the index finger and associated cam follower relatively to the cam wheel, the resilient flat paws 164 are arranged extending from each side of the frame and engage the racklike member 166, thereby inhibiting free lateral movement of the frame on the bar.

In operation, after the index finger has been moved along the rack to a position adjacent the indicia corresponding to the selected telephone number, it is desired to switch the motor on simultaneously with depressing the cam follower into operative engagement with the initial depressed surface of the cam wheel. Our description will now be concerned with such means and the means for shutting off the motor so that the initial depressed surface of any cam wheel, corresponding to the first station of telephone number combination of that cam wheel, will be spontaneously positioned adjacent the index finger in proper position to commence the dialing cycle again.

Referring now particularly to Figures 5 and 6, the toggle switch 167 of the conventional design for opening and closing the motor circuit is secured in the casing to the base thereof in any suitable manner. The substantially vertical arm 118 of the bell crank lever is pivotally connected to the link 168 by means of the pin 170. The lower end of the said link is fixed to the pin 172, which pin is pivoted in the horizontal link 174. The outer end of the horizontal link is pivotally connected to the switch actuating rocker arm 176 which is pivoted intermediate its ends to the motor switch frame 178. The movable and cylindrical switch electrode 180 is carried between the pin 182 arranged on the outer end of the rocker arm and the curvilinear upper surface 184 of the switch frame. The pin is adapted to enter the slot 188 on the electrode frame 190, an expanding spring 192 urging the electrode away from the pin. As the substantially vertical arm 118 is rocked in the direction indicated by the arrow in Figure 13 on depressing the indicator frame, the links just described swing the switch rocker arm about its pivot 190 forcing the movable electrode from the position shown in dotted lines in Figure 3 to assume the position shown in full lines in said figure and thereby into operative contact with the fixed electrode 194 of the toggle switch, thereby completing the motor circuit through the lead wires 196 and 198 which are operatively connected to the motor and the motor electrical circuit.

In order for the movable electrode to be forced into contact with the fixed electrode, the rocker arm pin is required to be urged completely home in the slot, thereby compressing the spring. This position is reached when the rocker arm is in a substantially vertical position.

Further motion of the rocker arm about its pivot toward the left of the switch frame, as viewed in Figure 3, urges the cylindrical movable electrode to snap along the curved surface of the frame toward and into contact with the fixed electrode. It will be apparent that considerable motion of the connecting linkage will be obtained before the electrode is snapped to open or close the switch.

As pointed out hereinabove, the height of the cam nose is sufficient only to permit disengagement of the clutch, and by reason of the play permitted in the connecting linkage the horizontal link 174 may be returned a considerable distance in the direction of the arrow shown in Figure 3 by the action of such cam nose without disengaging the switch electrodes, such movement of the horizontal link being taken up by the movement of the pin in the slot of the electrode frame.

It will be apparent, therefore, that the cam nose in disengaging the friction wheel will not disconnect the motor switch. Operative disconnection of the switch is accomplished by the cooperating detents 200 and 202 which are arranged respectively on the cam shaft and switch lever actuating link 204.

The detents normally assume the relative positions shown in Figure 5 when the elements of the device are disposed in normal inoperative stationary position. The detent 202 is rockably secured intermediate the switch lever actuating link 204, which is pivotally secured to the block arranged on the cam shaft support by means of the cap bolt 206. The detent 202 is inhibited from rotating about the pin 203 which secures it to the link in any suitable manner as by the pair of lugs 205 engaging the side of the link.

The lower end of the pivoted link 204 is secured to the link 172. The flat spring 208, the fixed end of which is secured to the pin 172 and the movable end 210 of which is secured to the detent 202, urges the said detent against the cam shaft 5: detent 200.

As the cam shaft and associated detent are rotated in the direction indicated by the arrow in Figure 5, the beveled nose 207 of the detent 202 is urged against the cylindrical surface 209 of 10: the detent 200 by the flat spring 208. The detents are so positioned relatively to each other and any cam wheel that they assume the position shown in Figure 5 when the cam follower is in contact with the rearward beveled edge 212 of 15: the last cam nose 156 of any cam wheel.

It will be apparent, therefore, that as the cam shaft detent is rotated during the operation of the device to a position just prior to that described (see Figure 6), the noses of the respective detents will engage to swing the pivoted arm about its pivot in the direction of the arrow indicated in Figure 6. Such motion of the pivoted arm through the respective connecting linkage members will swing the switch rocker arm about 25: its pivot 214 in the direction of the arrow shown in Figure 3, thereby disconnecting the motor switch.

The various members and detents are positioned relatively to each other so that the motor 30: switch will be disconnected just when the nose 216 of the cam shaft detent passes the nose 207 of the switch lever actuating link detent.

It will be apparent, therefore, that the motor switch will always be disconnected and the motor 35: stopped so that each cam wheel spontaneously assumes its normal stationary starting position, the switch actuating detents assuming the position illustrated in Figure 5. The inertia of the gears and moving parts of the device serves 40: to stop the motion of the respective parts of the device instantaneously the motor is disconnected, inhibiting any continued motion thereof.

It will be apparent that we have provided means which will switch the operating motor 45: arm upon moving the cam follower into operative engagement with the cam wheel and means for spontaneously shutting off the operating motor and positioning the cam follower relatively to any cam wheel in proper position to commence 50: the dialing cycle again.

It will be seen that to operate the device it is only necessary to depress the cam follower into engagement with a selected cam wheel, the motor thereby being started to drive the friction 55: clutch and cam wheel, which operate to automatically and successively in proper sequence rotate the telephone dial or influence any other associated device setting up impulses in the telephone call number selecting mechanism to obtain 60: the desired call number, the device spontaneously stopping its operation and returning the parts to their original stationary related positions after the telephone call number has been dialed or the impulses in the call number selecting mechanism set up.

It will be further apparent that we have provided an automatic telephone dialing device which is compact, portable, and which may be readily, conveniently and detachably associated 70: with a conventional automatic dial telephone hand set.

It will be further apparent that we have provided such a dialing device which may be selectively operated by the user to automatically dial 75:

telephone call numbers selected by the user from a pre-established group of such telephone call numbers.

It is understood that the particular embodiment described above is intended to be merely illustrative and not limitative of the invention, since it is obvious that the invention may be effected by apparatus arranged in many other different ways, within the scope of the appended 10 claims in which the intent is to set forth all the novelty over the prior art.

We claim:

1. Automatic dialing apparatus for association with a telephone instrument having a conventional rotary dialing disc comprising means for supporting the telephone instrument in fixed position upon the apparatus, a rotating friction disc normally disengaged from the dialing disc and adapted to progressively engage the edge of the 20 dial disc to turn the same, pivoted supporting means for the said dial engaging disc, cam means adapted to actuate said pivoted support to swing said dial disc engaging disc in and out of engagement with the said dial disc, and means to continuously rotate the said dial disc engaging disc during the dialing operation.

2. Automatic dialing apparatus for association with a telephone instrument having a conventional rotary dialing disc comprising a rotating friction disc normally disengaged from the dialing disc adapted to progressively engage the edge of the dial disc to turn the same, pivoted supporting means for the said dial engaging disc, cam means adapted to actuate said pivoted support to swing said dial disc engaging disc in and out of engagement with the said dial disc, and means to continuously rotate the said dial disc engaging disc during the dialing operation.

3. Automatic dialing apparatus for association with a telephone instrument having a conventional rotary dialing disc comprising means for supporting the telephone instrument in fixed position, a rotary shaft positioned adjacent the said instrument supporting means, dial disc engaging rotating friction disc normally disengaged from the dialing disc and in rotary engagement with the said shaft and adapted to progressively and rotatably engage the edge of the dial disc, means for supporting the said dial disc engaging disc swingably mounted adjacent the said shaft in position to continuously maintain the said shaft and dial disc engaging disc in rotary engagement, rotary cam supporting means adjacent the said shaft, cam following means pivotally mounted adjacent the said cam supporting means and in engagement with the swingable supporting means and adapted to be influenced by a cam on the cam supporting means to swing said swingable supporting means to bring the said dial disc engaging disc successively in and out of engagement with the dial disc.

4. Automatic dialing apparatus for association with a telephone instrument having a conventional rotary dialing disc comprising means for supporting the telephone instrument in fixed position, a rotary shaft positioned adjacent the said instrument supporting means, dial disc engaging rotating friction disc normally disengaged from said dialing disc and in rotary engagement with the said shaft and adapted to progressively and rotatably engage the edge of the dial disc, means for supporting the said dial disc engaging disc swingably mounted adjacent the said shaft in position to continuously maintain the said shaft and dial disc engaging disc in rotary engagement with the said rotary shaft, cam following means pivotally and slidably mounted adjacent the said shaft in position to continuously maintain the said shaft and dial disc engaging disc in rotary engagement, a cam supporting shaft in rotary engagement with the said rotary shaft, cam following means pivotally and slidably mounted adjacent the said shaft in

engagement, a cam supporting shaft in rotary engagement with the said rotary shaft, cam following means pivotally mounted adjacent the said cam supporting shaft, and in engagement with the said supporting means and adapted to be influenced by a cam mounted on the cam supporting means to swing said supporting means to bring the said dial disc engaging disc in and out of engagement with the dial disc.

5. Automatic dialing apparatus for association with a telephone instrument having a conventional rotary dialing disc comprising means for supporting the telephone instrument in fixed position, a rotary shaft positioned adjacent the said instrument supporting means, dial disc engaging rotating friction disc normally disengaged from said dialing disc and in rotary engagement with the said shaft and adapted to progressively and rotatably engage the edge of the dial disc, means for supporting the said dial disc engaging disc swingably mounted adjacent the said shaft in position to continuously maintain the said shaft and dial disc engaging disc in rotary engagement, rotary cam supporting means adjacent the said shaft, cam following means pivotally mounted adjacent the said cam supporting means and in engagement with the said supporting means and adapted to be influenced by a cam to swing said supporting means to bring the said dial disc engaging disc in and out of engagement with the dial disc, and means for simultaneously rotating the said rotary shaft and the said cam supporting shaft.

6. Automatic dialing apparatus for association with a telephone instrument having a conventional rotary dialing disc comprising means for supporting the telephone instrument in fixed position, a rotary shaft positioned adjacent the said instrument supporting means, dial disc engaging rotating friction disc normally disengaged from said dialing disc and in rotary engagement with the said shaft and adapted to progressively and rotatably engage the edge of the dial disc, means for supporting the said dial disc-engaging disc swingably mounted adjacent the said shaft in position to continuously maintain the said shaft and dial-disc-engaging disc in rotary engagement, a cam supporting shaft in rotary engagement with the said rotary shaft, cam following means pivotally and slidably mounted adjacent the said cam supporting shaft, and in engagement with the said swingable, supporting means and adapted to be influenced by a cam mounted on the cam supporting shaft to swing said swingable supporting means to bring the said dial disc engaging disc successively in and out of engagement with the dial disc, and means for rotating the said rotary shaft.

7. Automatic dialing apparatus for association with a telephone instrument having a conventional rotary dialing disc comprising means for supporting the telephone instrument in fixed position, a rotary shaft positioned adjacent the said instrument supporting means, dial disc engaging rotating friction disc normally disengaged from said dialing disc and in rotary engagement with the said shaft and adapted to progressively and rotatably engage the edge of the dial disc, means for supporting the said dial disc engaging disc swingably mounted adjacent the said shaft in position to continuously maintain the said shaft and dial disc engaging disc in rotary engagement, a cam supporting shaft in rotary engagement with the said rotary shaft, cam following means pivotally and slidably mounted adjacent the said shaft in

the said cam supporting shaft, and in engagement with the said supporting means and adapted to be influenced by a cam mounted on the cam supporting means to swing said supporting means to bring the said dial disc engaging disc in and out of engagement with the dial disc.

8. Automatic dialing apparatus for association with a telephone instrument having a conventional rotary dialing disc comprising means for supporting the telephone instrument in fixed position, a rotary shaft positioned adjacent the said instrument supporting means, dial disc engaging rotating friction disc normally disengaged from said dialing disc and in rotary engagement with the said shaft and adapted to progressively and rotatably engage the edge of the dial disc,

means for supporting the said dial disc engaging disc swingably mounted adjacent the said shaft and dial disc engaging disc in rotary engagement, a cam supporting shaft in rotary engagement with the said rotary shaft, cam following means pivotally and slidably mounted adjacent the said cam supporting shaft, and in engagement with the said swingable supporting means and adapted to be influenced by a series of cams mounted on the cam supporting shaft to swing said swingable supporting means to bring the said dial disc engaging disc successively in and out of engagement with the dial disc, and means for rotating the said rotary shaft.
